UNITED STATES PATENT OFFICE.

WILLIAM E. LUNDGREN, OF AUBURN, MASSACHUSETTS, ASSIGNOR TO COMMON-
WEALTH FINANCE CORPORATION, OF WORCESTER, MASSACHUSETTS, A CORPO-
RATION OF MASSACHUSETTS.

TENSION DEVICE FOR AUTOMATIC LOOM SHUTTLES.

Application filed March 8, 1928. Serial No. 260,118.

The invention relates to tensioning devices incorporated in shuttles, by means of which a uniform and sufficient tension is exerted on the weft in order that the goods may be woven properly. The invention has particular utility in shuttles provided for automatic silk looms, because the problem of proper tension has been a difficult one in this class of weaving.

10 In silk weaving, it has always been necessary to exert a considerable tension on the weft to prevent the finished goods from having wrinkles or other defects. This is particularly true in the weaving of crepes, where 15 one or two loose weft threads would ruin the whole piece of goods because the twist in the weft would then destroy the symmetry of the fabric. It is this factor that has, more than anything else, retarded the acceptance of the 20 automatic weft replenishing loom by the silk industry. However, the automatic principle of weaving is now being adopted by silk manufacturers in spite of the above difficulty because of the demand for greater production 25 and lowered cost.

I am aware that many forms of self-threading tensioning devices for automatic shuttles exist in the art and that some of these have been used with more or less success in the silk 30 industry. There is, however, one feature which substantially all of these prior devices have which limits their effectiveness, and this is the employment of the drag of the weft itself from the bobbins or quills to actuate the 35 self-threading tensioning device. Such employment places a definite limitation on the amount of tensioning which the device can be made to exert, and this limitation of effectiveness has, in most instances, caused the self-threading tensioning devices to exert a much less tension than the manually threading tensioning devices heretofore and now in use.

The device of my invention has no such 40 limitations and can exert a tensioning force 45 far in excess of the drag of the silk off the bobbin. Furthermore the device is self-contained, incorporated in the shuttle, and depends upon no outside mechanical means for its operation. By my invention I make use 50 of the inertia of a mass of material mounted in the shuttle to place the elements of the tensioning device in threading position, a spring or some resilient means then being utilized to

exert the tension. As the inertia of a mass of material in the shuttle can be used to overcome the tension of a spring or resilient device having considerable resistance, I am enabled to exert a tension up to any required limits. The inertia of the mass derives its reactant force from the rapid acceleration of 60 the shuttle when it is picked out of the shuttle box.

The means which I have employed to effect the threading of a tensioning device may be widely varied; I have illustrated in the drawing and will describe herein a particular embodiment of such which is the best form now known to me. In the said drawings:—

Fig. 1 is a plan view of an automatic loom shuttle incorporating the tensioning device 70 and mechanism of my invention.

Fig. 2 is a fragmentary plan view of the eye end of the shuttle with a portion of the device broken away to better show the operating mechanism.

Fig. 3 is a view similar to Fig. 2 but showing the elements of the tensioning device in position for threading.

Fig. 4 is a sectional view on the line 4, 4, of 80 Fig. 2.

Fig. 5 is a transverse sectional view on the line 5, 5, of Fig. 3.

Figs. 6 and 7 are schematic views of the elements of the tensioning device before and during threading.

Fig. 8 is a perspective view of the tensioning mechanism.

Fig. 9 is a plan view of a modified form of tensioning mechanism.

Like reference characters refer to like 90 parts throughout the drawing.

Referring first to Fig. 1, the body of an automatic shuttle is indicated at 1, said shuttle having the usual tips 2, 2, and being provided with a spring fork 3, and heel plate 4, peculiar 95 to automatic loom shuttles. It is to be understood that my invention can be applied to any type of automatic loom shuttle.

The tensioning device of the invention is desirably completely contained in a metal casing 5, which may be of the general form and shape shown in the several figures and which can be inserted in or removed from a depression 6 formed in the threading end of the shuttle for this purpose. Referring particularly to Figs. 2, 3, 4, and 5, the casing 5 com-

prises a bottom plate 7, one end of which flares outwardly when viewed in plan and to which are integrally attached a pair of vertical supports 8, 8, providing top plates 9, 9^a, integrally formed therewith. In this manner the casing provides an inclosed space for the reception of the actuating mechanism of the tensioning device leaving a passage 10, between the plates 9, 9^a, for the passage of the thread.

Extending between the inner edges and top plates 9, 9^a, and the bottom plate 7 of the casing and screwed into the latter when the mechanism is assembled are a pair of vertical pivot posts 11, 11. These may best be seen in Figs. 2, 3, and 5. The posts 11, 11, serve for the pivotal support of elements of the tensioning device. The latter comprise continuous wires 12 and 13, the former having three hook portions 14, 14, 14, and the latter having a pair of hook portions 15, 15. Each wire tensioning device is wound into coils 16 and 17 respectively which surround the pivot posts 11, 11. Those portions of the wires 12 and 13 which carry the hooks 14 and 15 respectively lie close to or touching the bottom plate 17 and join the coils 16 and 17 at the bottom thereof; the tops of the coils 16 and 17 extend tangentially to form arms 18 and 19 respectively which merge into a second set of coils 20 and 21 at the ends of said arms. The bottom of the coil 21 provides a closed eye 23 while the bottom of the coil 20 provides an open eye 22. The coils 20 and 21 serve to support inertia masses 24 and 25 which may be formed of any desirable substance such as lead, and an elastic 26 connects them, the elastic being held by the eyes 22 and 23.

In other respects the shuttle threading mechanism may incorporate or provide any desired form of horn and shuttle eye. As herein shown the top plate 9^a extends forwardly and terminates in a depending and leftward extending horn 27 which may be of any usual shape. Between the underneath portion of said horn and the bottom plate 7 is an inclined pin 28 under which the filling passes when the shuttle is fully threaded. The open eye 29 completes the threading apparatus of the shuttle so far as concerns my invention.

In considering the operation of my novel tensioning mechanism let it be assumed that the shuttle 1 is in the right hand box of an automatic loom underneath the magazine or battery thereof and that a full bobbin 30 has just been placed in position as shown in Fig. 1 by the transferring mechanism of the loom. The filling end 31 will at that time, as is well known to those familiar with this art, extend directly from the bobbin 30 to the filling holding knob or bell provided by the loom to hold the ends of filling from bobbins placed in the magazine, and the filling will thus be above

the level of the tensioning mechanism. I make use of the following flight of the shuttle to draw the thread downward past the opening 10 around the horn 27, and into the tensioning mechanism precisely as is done in all shuttles and threaders of this class. The novelty of the present apparatus consists in utilizing the acceleration given to the shuttle by the picker stick, as the shuttle moves out of the box, to cause the hooks 14 and 15 to overlap as shown in Fig. 3, this being occasioned by the inertia of the masses 24 and 25 which, since the shuttle is violently propelled to the left, tend to move to the right relative to the shuttle body, thus placing the parts in the position shown in Figs. 3 and 7. The hooks 14 and 15 having been thus placed in overlapping position, the filling end 31 will be received between them, and the subsequent separation of the arms 12 and 13 which separates the hooks 14 and 15 threads the tensioning mechanism as shown in Fig. 2. Of course, as in previous shuttles, the filling does not pass through the open eye 29 until the return pick of the shuttle. Since the force which causes the wires 12 and 13 to come together overlapping the hook portions 14 and 15 is derived from a source independent of the pull of the thread, and in fact may be a very considerable force even with inertia masses no larger proportionately than the masses 24 and 25 shown in the figures, the tension of the elastic 26 can be regulated to produce a very strong tension on the filling end 31 during the weaving of the goods, and thus the results set forth at the beginning of this specification are fully achieved. In order to easily insert and adjust the tension of the elastic 26 a knot may be made at one end thereof and, the elastic being pulled through the eye 23, and a knot having been made at the other end the proper distance from the first knot to provide the desired tension, the second knot may be slipped under the open eye 22. A hole 32 is provided in the side of the shuttle for easy access to the device for this purpose. It will be obvious to all that I may substitute a metal spring for the elastic 26 and in fact any form of resilient means will serve the purpose.

Preferably a raised portion 33 may be provided on the bottom plate 7 to cause the filling to clear the elastic 26 or equivalent resilient means. The metal casing 5 may be fastened in position in the shuttle by means of a horizontal screw 34.

Figs. 6 and 7 show diagrammatically the hooks 14 and 15 prior to and at the time of the flight of the shuttle, the filling end 31 being shown in proper relative position. Fig. 8 shows the tensioning and threading mechanism in perspective detached from the casing 5 so that the parts thereof may be more clearly visualized. It will be understood that the masses 24 and 25 are desirably made of lead because of the high specific gravity of this

metal and the fact that it can be easily shaped or trimmed with a knife.

In Fig. 9 a slightly modified form of tensioning device is shown in plan view detached from the casing. In this figure a vertical pivot post is shown at 11^a and a single wire tensioning device 12^a is provided, the latter having three hook portions 14^a. The wire 12^a is turned into a coil 16^a and a coil 20^a exactly as in the other form of the invention, these coils being connected by a short arm 18^a. The coil 20^a carries a mass 24^a the inertia of which swings the wire 12^a from the full line position to the dotted line position 15 against the tension of an elastic 26^a. The hook portions 14^a are adapted to overlap a series of pins 35 and when the device springs back to its original position the apparatus is threaded. It will be seen that the modified form of mechanism works in exactly the same manner as the forms shown in Figs. 1 to 8 inclusive, except that only one set of movable elements are provided.

Although designed primarily for automatic looms the device of the invention may be used in connection with non-automatic looms and has considerable utility for such, since the filling can be caused to thread in the tensioning mechanism of the invention 30 by merely giving the shuttle a sharp whip with the hand in a manner that will be easily learned by those familiar with this art.

As I believe I am the first to use means actuated by the acceleration of a shuttle to effect a tensioning of or to put a drag on the filling in said shuttle, I wish to claim the same broadly, however carried out, and in the appended claims the term "acceleration" is to be taken to include negative as well as 40 positive acceleration, and the word "inertia" is to be taken to mean the property which all matter (so far as known) possesses, of resisting any attempt to start it if at rest, to stop it if in motion, or in any way 45 to change either the direction or amount of its motion.

I claim:

1. In a device of the class described, a movable thread tensioning member, resilient means holding said member in thread tensioning position, and an inertia mass and connections whereby said tensioning member is moved to threading position upon the pick-

ing of the shuttle in which the device is located. 55

2. In a device of the class described, a pair of movable thread tensioning members, resilient means holding said movable members in thread tensioning position, and inertia masses and connections whereby said tensioning members are moved to threading position upon the picking of a shuttle in which the said device is located. 60

3. In a device of the class described, a pair of pivot pins, a pair of levers mounted on said pins, hooked portions on each of said levers, adapted upon the swinging of said levers in opposite directions to overlap, and inertia means on the other arms of said levers whereby to swing them together upon the picking of a shuttle in which the said device is located. 65

4. In a device of the class described, a pair of pivot pins, a pair of levers mounted on said pins, hooked portions on each of said levers, adapted upon the swinging of said levers in opposite directions to overlap, and inertia means on the other arms of said levers whereby to swing them together upon the picking of a shuttle in which the said device is located and resilient means connecting said levers whereby to thereafter separate said hooked portions to exert a tension on a thread. 75

5. In a device of the class described, a wire twisted into a pair of coils and having a plurality of hooked portions formed thereon, a pivot post adapted to receive one of said coils, and a weight contained in the other of said coils, whereby the end of said wire having said hooked portions is moved upon the impacting of a shuttle containing said device in order that the hooked portions may receive and tension a thread. 85

6. In a device of the class described, a thread tensioning device, resilient means adapted to hold said device with a force great enough to exert a tension on filling greater than the drag of the filling off the bobbin, and inertia means adapted upon acceleration of a shuttle in which said device is placed to move said device to receive a thread, whereby the subsequent movement of said device in response to said resilient means will exert the tension aforesaid. 95

WILLIAM E. LUNDGREN.
